UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

VAPOR-GENERATING APPARATUS.

No. 892,097.

Specification of Letters Patent.

Patented June 30, 1908.

Original application filed June 9, 1898, Serial No. 683,000. Divided and this application filed October 14, 1902.

Serial No. 127,227.

To all whom it may concern:

Be it known that I, ELIHU THOMSON, a citizen of the United States, residing at Swampscott, in the county of Essex, State of Massachusetts, have invented certain new and useful Improvements in Vapor-Generating Apparatus, of which the following is a specification.

The present application is a division of my 10 pending application Serial No. 683,000, filed June 9, 1898, which division is made under the requirements of the United States Patent Office.

In order to produce high-pressure vapor, 15 such as superheated steam, under economical conditions, it is necessary to supply water to the boiler and fuel to the fire chamber in certain amounts, which amounts bear a definite relation to each other and are varied to suit 20 the requirements of service. It is also desirable to supply an amount of air to the fire chamber which is sufficient to support combustion and to increase or decrease this amount in accordance with the changes in 25 the amount of fuel.

One object of the present invention is to provide a vapor-generating system wherein the amount of fluid supplied to the generator and fuel supplied to the fire chamber can be 30 readily varied to suit the requirements of service, and this in a simple and economical manner.

A further object of the invention is to provide a vapor-generating system wherein the supply of fluid to the generator and fuel and air to the combustion chamber can be simultaneously controlled in a manner to preserve the economy of the system at all times.

For a consideration of what I consider to 40 be novel and my invention attention is called to the accompanying description and claims appended thereto.

In the accompanying drawing is illustrated 45 a flash boiler together with water, fuel and air pumps for supplying water to the generator and fuel and air to the combustion chamber, together with suitable regulating means therefor.

1 represents a flash boiler, which is designed 50 to supply superheated vapor and is inclosed by a casing 2. The boiler grids 3 are inclosed by an inner casing, and between this casing and the outer one is a chamber 4 for receiving and heating the feed water.

The tank 5 containing water or other liquid 55 is connected with the lower end of the chamber 4 by the pipe 6. The boiler may be of any suitable construction wherein a relatively small space is provided for the water so that there can be no considerable storage 60 space for hot water and steam. Water to the boiler is supplied by the power pump 7 which has the usual suction and delivery valves 8 and 9. The suction side of the pump is connected to the upper end of the 65 feed water heating chamber 4 by means of the pipe 9^a. A valve 10 is included in the pipe so that the passage of water therethrough can be controlled. The delivery side of the pump is connected by the pipe 11 70 with the inlet end of the boiler, which in the present instance is at the lower extremity of the structure, and the passage of water in the boiler is toward the fire, that is to say, water is delivered to the coolest part of the boiler, 75 and as it flows therethrough it approaches nearer and nearer to the combustion chamber. At some intermediate point in its passage the water or other liquid is flashed into vapor and from that point on to the delivery 80 end of the boiler it is gradually superheated. The degree of superheat depends upon the amount of liquid forced into the boiler and also upon the amount of heat maintained by the fire chamber. Between the pipes 9^a and 85 11 is an adjustable by-pass 12 by means of which the proportionality between the water and fuel pump can be adjusted. That is to say, if the water pump delivers an amount of water which is in excess, it can be adjusted 90 by slightly opening the by-pass and a certain amount of water will flow in a local circuit.

The fire chamber comprises a receptacle 13 made out of heat resisting material and containing a mass of broken fire-brick 14 through 95 which the products of combustion pass on their way to the boiler. The mass of fire-brick or other material of a similar nature is sustained in position on a grate 15. Situated above the mass of broken fire-brick is a 100 second grate 16 which serves as a retaining means. Surrounding the fire chamber is a metal casing 17, and between this casing and the outer one is an air chamber 18 in which the air is heated before it is supplied to the 105 burner.

The burner consists of a detachable head or plug 19 which is retained in place by clamps

20. In the head is formed an air passage 21 that registers with a corresponding passage in the casing. Other passages for the air are also provided which extend substantially at 5 right angles to passage 21. It is also provided with a fuel passage 22 that registers with a fuel passage 23 in the casing. In addition to this small fuel carrying passages opening into the fire chamber are provided. 10 Fuel for the system is supplied from the tank 24, and a power pump 25 is placed in circuit therewith so that the fuel may be delivered to the fire chamber under relatively high pressure. Situated between the burner 15 and the grate 16 is a mixing chamber 30 in which the air and fuel are mixed and burned. Air is supplied to the chamber 18 by the power driven air pump 31, and on the air pump structure are mounted the fuel and 20 water pumps. The air pump is connected to the chamber 18 by a pipe 32, and admission of air to the pump is had through any convenient opening. The fuel and water pumps are driven by the eccentrics 33 and 25 34 which are mounted on the shaft 35, the latter being the shaft which drives the air pump and carries the pulley 36 shown in dotted lines.

From the foregoing it will be seen that as 30 the speed of the driving shaft 35 changes, the amounts of water, fuel and air delivered by their respective pumps will be simultaneously and correspondingly varied, owing to the fixed relation of the pumps.

35. In order to change the speed of the pump-driving shaft 35 to compensate for changes in load on the system, two cone pulleys 37 and 38 are provided which are constructed in the ordinary manner. Connecting the 40 pulleys is a belt, and a lever 40 is provided which may be actuated in any suitable manner to shift the position of the belt and thus change the speed at which the pulley 37 is driven, and consequently that of the pump 45 shaft 35. The pulley 38 is belted, as is shown in dotted lines, to a pulley carried on the shaft of the engine 41. The engine receives steam from the boiler through the pipe 42, and the admission of steam to the engine 50 is controlled by the valve 43 which is operated by the handle 44. Steam is admitted to the engine cylinders by valves 45, which are under the control of the cam 46, the cam being connected to the engine shaft by a driving connection 47. The exhaust from the 55 engine is carried by the pipe 48 into the downwardly opening flue 49 where it is employed to increase the draft of the fire chamber.

The engine may be employed to propel a 60 vehicle as well as to drive the pumps if desired, or it may drive the pumps alone.

To start the apparatus into operation, the plug 19 is removed and heated to a temperature sufficient to easily vaporize the oil coming in contact therewith. A torch is then

applied to fire the oil at the opening and the plug returned to place and secured by the clamp 20. At the start the air and oil pumps are driven by some extraneous means, and the water pump rendered inoperative by 70 shutting off its suction pipe by the valve 10. The air from the pipe 32 passes upward through the chamber 18 where it is heated prior to passing through the openings in the plug 19. The combustion which takes place 75 within the chamber 30 raises the lining and entire mass of fire-brick to a high temperature, and the vaporizer or boiler soon attains a temperature which is sufficient to generate vapor. As soon as the generator is hot the 80 engine 41 may be started by rendering the water pump active by opening the valve 10, after which the combustion of vapor causes the generator to furnish vapor and the engine may be employed to furnish the pump- 85 ing power.

In accordance with the patent statutes I have described the principle of operation of my invention, together with the apparatus which I now consider to represent the best 90 embodiment thereof, but I desire to have it understood that the apparatus shown is only illustrative, and that the invention can be carried out by other equivalent means.

What I claim as new and desire to secure 95 by Letters Patent of the United States, is—

1. The combination with a steam generator wherein the heating power is supplied by a liquid fuel burner, of a pump and connections for supplying fuel to the burner, a pump and connections for supplying water to the generator, means for uniting the pump pistons, means for driving the pumps, and means intermediate the driving means and the pumps for simultaneously changing 105 the speed of the pumps without changing the speed of the driving means in a manner to cause corresponding variations in the supply of fuel and water furnished to the burner and to the generator. 110

2. The combination of a steam generator wherein the heating power is supplied by a liquid fuel burner, a pump and connections for supplying fuel to the burner, a pump and connections for supplying water to the generator, a pump and connections for supplying air to the burner, an engine for driving the pumps, and means intermediate the engine and the pumps for simultaneously changing the speed at which the pumps are 120 driven so as to cause corresponding variations in the supply of fuel, air and water furnished to the burner and generator. 115

3. In combination, a generator of the flasher type arranged to supply superheated 125 vapor, a pump for supplying liquid thereto, a fire chamber, a pump for supplying liquid fuel thereto, a single driving means for both pumps, and a speed-changing mechanism intermediate the driving means and the 130

pumps whereby the capacities of the pumps can be varied without changing the speed of the driving means.

4. In combination, a generator of the flasher type arranged to supply superheated vapor, a pump for supplying liquid thereto, a fire chamber, a pump for supplying liquid fuel thereto, a pump for supplying air to the fire chamber, a driving means common to the 10 pumps, and a speed-changing mechanism intermediate the driving means and the pumps for varying the effective delivery of the latter.

5. The combination with a boiler, a 15 burner therefor adapted to burn a mixture of air and liquid fuel, a body of heat-resisting material between the burner and the boiler which serves to heat the latter, and an inclosing casing for the boiler, burner and said 20 material, of a pump for supplying liquid to the boiler, pumps for supplying air and fuel to the burner in definite proportions, a common actuator for the boiler and burner supply pumps, and a controller between the actuator and said pumps for changing the 25 speed of the pumps.

6. The combination of a flash boiler, a means for heating the boiler which comprises a fire chamber and a body of heat 30 resisting material, a pump for supplying liquid to the boiler, pumps for supplying air and

fuel to the means for heating the boiler in definite proportions, a common actuator for the liquid, air and fuel supply pumps, and a controller between the actuator and said 35 pumps for changing the speed of the latter.

7. The combination of a generator, a fire chamber, a feed water heater heated by the fire gases, a tank for the water supply, a pump for circulating water from the tank 40 through the heater and supplying it to the generator, a pump supplying fuel to the fire chamber, means for simultaneously driving the pumps, and means for simultaneously changing the speed of the pumps without affecting the speed of the driving means. 45

8. The combination of a generator, a burner, a casing for both, a chamber in the casing in which liquid is heated by the fire gases, a tank from which liquid flows to the 50 chamber, a pump for delivering water to the generator, a pump for supplying fuel to the burner, a motor for the pumps, and means independent of the motor for changing the speeds of the pumps. 55

In witness whereof, I have hereunto set my hand this tenth day of October, 1902.

ELIHU THOMSON.
